US00D904985S

(12) **United States Design Patent** (10) Patent No.: **US D904,985 S**
(45) Date of Patent: **** Dec. 15, 2020**

(54) **ELECTRONIC CABLE**

(71) Applicants: **Evan Spiegel**, Santa Monica, CA (US);
Mathias Andreas Hintermann, Playa Vista, CA (US); **Tanatip Arunanondchai**, Santa Monica, CA (US); **Lauryn Morris**, Culver City, CA (US)

(72) Inventors: **Evan Spiegel**, Santa Monica, CA (US);
Mathias Andreas Hintermann, Playa Vista, CA (US); **Tanatip Arunanondchai**, Santa Monica, CA (US); **Lauryn Morris**, Culver City, CA (US)

(73) Assignee: **Snap Inc.**, Santa Monica, CA (US)

(**) Term: **15 Years**

(21) Appl. No.: **29/674,957**

(22) Filed: **Dec. 27, 2018**

(51) LOC (12) Cl. **13-03**

(52) U.S. Cl.

USPC **D13/153**

Primary Examiner — Rhea Shields

(74) Attorney, Agent, or Firm — Culhane Meadows PLLC; Stephen J. Weed

(57) **CLAIM**

The ornamental design for an electronic cable, as shown and described.

DESCRIPTION

FIG. 1 is a front perspective view of an electronic cable; FIG. 2 is a front view thereof; FIG. 3 is a rear view thereof; FIG. 4 is a left side view thereof; FIG. 5 is a right side view thereof; FIG. 6 is a top view thereof; and, FIG. 7 is a bottom view thereof.

The electronic cable is shown with a symbolic break in its length. The appearance of any portion of the article beyond the break line forms no part of the claimed design. Throughout the drawings, the broken lines in the drawings represent portions of the electronic cable that form no part of the claimed design.

1 Claim, 5 Drawing Sheets
